J. A. DE VITO.
CLEANING DEVICE.
APPLICATION FILED NOV. 5, 1919.

1,382,633.

Patented June 28, 1921.

UNITED STATES PATENT OFFICE.

JOHN A. DE VITO, OF WEST MEDFORD, MASSACHUSETTS.

CLEANING DEVICE.

1,382,633.

Specification of Letters Patent. Patented June 28, 1921.

Application filed November 5, 1919. Serial No. 335,906.

To all whom it may concern:

Be it known that I, JOHN A. DE VITO, a citizen of the United States, residing at West Medford, in the county of Middlesex 5 and State of Massachusetts, have invented an Improvement in Cleaning Devices, of which the following description, in connection with the accompanying drawings, is a specification, like characters on the drawings representing like parts.

The invention to be hereinafter described relates to devices for cleaning automobiles and for other purposes.

One of the purposes of the invention is to 15 provide a simple and efficient device for receiving water from the city main or other source of supply, thoroughly mixing soap with the water, and delivering the soapy water to the automobile or other article to 20 be cleaned.

Another purpose of the invention is to provide readily operable means for alternatively delivering soapy water or clear rinsing water to the automobile or other 25 article to be cleaned.

With the aforesaid and other objects in view, the character of the invention will be best understood by reference to the following description of one good form thereof 30 shown in the accompanying drawing.

In the drawing is shown a perspective view of a device embodying the invention, parts being broken away to disclose the internal construction of the device.

35 Referring to the drawing, the cleaning device shown therein as one embodiment of the invention, comprises a casing, in the present instance, in the form of a cylinder 1 having a head 3 conveniently cast integral with the cylinder, and an upper bumped head 5 secured to a flange 7 at the upper end of the cylinder by bolts 9, a packing ring 11 being interposed between said head and flange to prevent leakage.

40 The cylinder 1 may have suitable provision for readily admitting a supply of soap therein from time to time as required. To accomplish this, in the present instance, the cylinder is provided with a neck 13 threaded to receive a cap, 15 having diametrically opposed handles 17 to enable the cap readily to be applied to or removed from the neck when required. A packing ring 19 may be interposed between the cap and the end of 45 the neck to prevent leakage.

Suitable means may be provided for agi-

tating the soap in the casing, and for thoroughly mixing the soap with the water passing through the casing, as more fully hereinafter described. To accomplish this, in 60 the present instance, a blade or blades conveniently in the form of a screw 21 is provided within the casing on a vertical shaft 23 having its lower end journaled in a bearing 25 in the lower head 3, and its upper end 65 journaled in a bearing 27 in the upper head 5.

Suitable means may be provided for rotating the screw shaft 23. This means, in the present instance, comprises a turbine 29 70 fast on said shaft conveniently adjacent the upper head 5. This turbine may be rotated by water from the city main or other convenient source of supply. To direct the water to the turbine, a nozzle 31 may be 75 mounted in the cylinder 1 adjacent the upper end thereof, and may be curved or disposed at an appropriate angle for delivering the water to the blades of the turbine. Water may be supplied to the nozzle 80 31 through a pipe 33 which may be connected to a faucet or other source of water supply. The pipe 33 may be provided with a valve 35 for controlling the supply of water to the nozzle. 85

Suitable means may be provided to conduct the soapy water from the casing. To accomplish this, in the present instance, a delivery pipe 37 may be entered through the cylinder 1 and receive water therefrom pref- 90 erably adjacent the lower end thereof. The delivery pipe 37 may be provided with a valve 39 for controlling the discharge therefrom, and the pipe 37 may be connected to a hose 41 provided with a nozzle 43 of usual 95 construction.

The casing may be divided into a soap containing chamber 45 and a discharge chamber 47. To accomplish this, in the present instance, a partition or plate 49 is 100 provided and supported on a rib or ledge 51 projecting inward from the cylinder 1. The plate 49 may be foraminated, in the present instance, by a multiplicity of circular perforations 53 distributed throughout the same. The construction is such that the body of the soap will be retained in the soap chamber 45, but the soapy water may readily pass through the foraminated plate 49 into the delivery chamber 47. 105

When the valves 35 and 39 are opened, water may pass through the supply pipe 110

and strike the blades of the turbine, thereby rotating the same at high speed. The water will thus be thoroughly agitated and delivered downward through the soap containing 5 chamber 45, where it will mix with the soap contained therein. The screw 21 will tend to elevate the soap up from the foraminated plate 49 and agitate the soap and water and thoroughly mix the same. The soapy water 10 will pass through the perforations in the plate 49 into the delivery chamber 47, and pass thence through the delivery pipe 37, the hose 41 and nozzle 43.

After the automobile or other article has 15 been treated sufficiently with the soapy water, it is desirable to apply clear rinsing water thereto to wash off the soapy water. To accomplish this, in the present instance, the water supply pipe 33 and the discharge 20 pipe 37 may be connected by a by-pass pipe 55 having its end secured to T-unions 57 and 59 connected into said pipes 33 and 37 respectively. The by-pass pipe may be provided with a control valve 58. This valve is closed 25 during the mixing of the water with the soap and the delivery of the soapy water from the device. When it is desired to cut off the supply of soapy water and apply the rinsing water, the valves 35 and 39 are closed, 30 and the valve 57 is opened. This will allow clear water to pass through the supply pipe 33, the by-pass pipe 55, the delivery pipe 37, the hose 41 and nozzle 43 to the automobile or other device to be rinsed.

35 The casing may be conveniently formed of a casting having sufficient weight to support the device in position for use without the necessity for securing the same in place. Preferably a liquid or readily soluble soap is 40 employed, and this soap may be readily introduced through the neck 13 into the casing as required.

The device is strong and simple in construction and easily operated. It serves to 45 rapidly and thoroughly mix the soap with the water so as continuously to deliver soapy water containing the proper percentage of soap for efficient cleaning effect so long as required. The proportion of soap in the 50 water will be readily varied by adjustment of the water supply valve 35. If this valve is throttled, it will slow down the turbine and produce less mixing effect than when the valve is wide open. Thus, the device 55 may be readily controlled so as to deliver a minimum amount of soap into the water consistent with efficient cleaning effect.

If reduction in the percentage of soap without reduction in the amount of water 60 delivered from the device is desired, the by-pass valve may be opened somewhat to allow some of the water to pass directly to the delivery pipe 37.

The device is cheap to manufacture, and 65 the parts may be quickly and easily assem-

bled, and the device is not liable to get out of order in use.

It will be understood that the invention is not limited to the specific embodiment shown, and that various deviations may be 70 made therefrom without departing from the spirit and scope of the appended claims.

What is claimed is—

1. A device of the character described, comprising a casing having a chamber 75 therein provided with an apertured bottom, an upright shaft mounted in said chamber, a turbine mounted on said shaft in said chamber, means to direct water against the turbine to rotate the same and agitate the water in the 80 chamber, a screw on said shaft in said chamber for elevating materials from the bottom of the chamber toward the turbine, that the materials may meet the water agitated by the turbine, and means to deliver the water and 85 materials mixed therewith from said chamber.

2. A device of the character described, comprising a casing having an apertured 90 partition therein dividing the same into upper and lower chambers, an upright shaft mounted in the upper chamber, a turbine on said shaft located in said chamber adjacent the upper end thereof, a pipe having a nozzle projecting into said chamber to direct water against the blades of the turbine to rotate the turbine, the latter being arranged to agitate the water in the upper chamber, a screw on said shaft for elevating soap or 95 other materials from said partition toward 100 said turbine to meet the water agitated by the latter, and a pipe to deliver the water and soap or other materials mixed therewith from the lower chamber.

3. A device of the character described, comprising a casing having an apertured 105 partition therein dividing the same into upper and lower chambers, an upright shaft mounted in the upper chamber, a turbine on 110 said shaft located in said chamber adjacent the upper end thereof, a pipe having a nozzle projecting into said chamber to direct water against the blades of the turbine to rotate the turbine, the latter being arranged to agitate the water in the upper chamber, 115 a screw on said shaft for elevating soap or other materials from said partition toward 120 said turbine to meet the water agitated by the latter, a pipe to deliver the water and soap or other materials mixed therewith from the lower chamber, a by-pass pipe connecting 125 said pipes, and valves for said pipes operable to allow water to pass through the casing to mix with the materials in the upper chamber thereof, or to pass through the by-pass pipe to deliver clear water through said pipes.

In testimony whereof, I have signed my name to this specification.

JOHN A. DE VITO.
